Attorney

UNITED STATES PATENT OFFICE.

ROBERT M. CLAPP, OF ALHAMBRA, CALIFORNIA.

SPOUT AND SEAL FOR CONTAINERS.

Application filed April 28, 1924. Serial No. 709,432.

To all whom it may concern:

Be it known that I, ROBERT M. CLAPP, a citizen of the United States, residing at Alhambra, in the county of Los Angeles and

State of California, have invented new and useful Improvements in Spouts and Seals for Containers, of which the following is a specification.

This invention relates to a dispensing application for cans, of the type which is adapted to be attached to a can to serve as a funnel and spout for facilitating removal of the can contents. It is customary in dispensing liquids from cans to punch two holes 15 in the top of the can at diametrically opposite points, through one of which openings the liquid may flow when the can is tilted, and through the other of which openings air may enter to replace the discharged 20 liquid.

It is the object of this invention to provide a device which may be readily applied to a can and remain attached thereto to serve as a spout for removal of the contents 25 and also serve as a means for closing the openings of the can end for protection of the contents, and which may be readily removed when desired.

Another object is to provide a device of 30 the above character which is adapted to be formed in one piece whereby it may be manufactured at small cost.

With the foregoing objects in view, together with such other objects and advantages as may subsequently appear, my invention resides in the parts and in the construction, combination and arrangement of parts as hereinafter described and claimed, and illustrated by way of example 40 in the accompanying drawings, in which—

Figure 1 is a perspective view illustrating the invention as applied.

Figure 2 is a view in longitudinal section of the device, as seen on the line 2—2 of 45 Figure 1.

Figure 3 is a plan view illustrating a modified form of the invention.

Figure 4 is a detail in perspective illustrating a modified form of one end portion 50 of the device.

Referring to the drawings more specifically, 3 indicates a device embodying the present invention and 4 designates a can to which the device is adapted to be applied.

55 The can is provided with an end wall 5 in which are punched an outlet opening 6 and

a vent opening 7 at diametrically opposite points; these openings being formed in the usual manner when it is desired to open the can.

The device 3 is preferably formed from a single integral strip of metal which strip is formed with an elongated longitudinally extending opening or slot 8 to provide a pair of spaced side members 9 and 10 which are adapted to extend across the top 5 of the can and to seat thereon; the side members 9 and 10 being slightly upturned at their end portions as indicated at 11 so as to form recesses 12 on the under side of the device 70 adapted to receive the margin of the can end wall 5 so that the intermediate portions of the side members 9 and 10 will seat on the depressed surface with which can ends are ordinarily formed so that the under sides 75 of the side members 9 and 10 will contact the can end to close the openings 6 and 7, as will presently be described.

The ends of the strip are formed with down-turned curved flanges 13 and 14 which are adapted to extend over and conform to the sides of the can. The outer ends of the slot 8 terminate at the flanges 13 and 14 so as to expose the margin of the can end 5 along the inner faces of the flanges 13 and 14, so that when the device is placed on the can, as shown in Figure 1, the openings 6 and 7 will be exposed through the slot 8. The end of the slot 8 adjacent the flange 13 is upturned to form a lip or flange 15 which 80 serves as a spout 16; the flange 15 being curved outwardly intermediate the side members 9 and 10 in continuation of the flange 13.

In the operation of the invention the device is placed on the can as shown in Figure 1 and positioned to expose the openings 6 and 7 when it is desired to pour the contents from the can; the device being arranged with the spout 16 located adjacent the outlet opening 6. It will now be seen that on tipping the can to pour the contents through the opening 6 the liquid will be directed from the opening over the spout 16. When it is desired to close the openings 6 and 7, the device is turned on the can to position one of the side members 9 and 10 over the opening 6, whereupon the other side member will be positioned over the vent opening 7. 95

While I have shown the slot 8, as in Figures 1 and 2, as extending continuously between the end flanges 13 and 14, it is obvi-

ous that only the end portions of the slot serve the purpose of exposing the openings 6 and 7, and only the end portions of the side members 9 and 10 serve to close the openings, and, accordingly, in some instances it may be desirable to form the device as shown in Figure 3; that is, with a top portion 17 having curved end flanges 18 and 19 corresponding to the flanges 13 and 14, and to provide openings 20 and 21 in the top member 17 adjacent the end flanges 18 and 19 to provide the spaces through which the openings 6 and 7 in the can end may be exposed.

15 The device being formed of sheet metal, will be resilient so that the end flanges 13 and 14 will serve as spring clips to engage the perimeter of the can top, but inasmuch as cans of certain sizes may vary somewhat in diameter it may be necessary to form the device so as to compensate for this variation, in which instance I construct the end of the device opposite the spout with a pair of spring clips 22 in lieu of the continuous 20 curved flange 14; the clips 22 being formed in continuation of the side members of the aperture through which the opening 7 in the can end is exposed. Each of the spring 25 clips 22 embodies a tongue 23 on a bow 24

projecting upwardly and outwardly from 30 the end of the device.

I claim—

1. A device of the character described, comprising a strip adapted to seat on the end of a can, said strip being formed with 35 curved down-turned end flanges adapted to conform to the margins of a can end, said strip being formed with an opening to expose holes punched in the can top, and a spout formed integral with the strip in continuation with one of the flanges and along 40 the margin of the opening in the strip.

2. A device of the character described, comprising a strip adapted to seat on the end of a can, said strip being formed with 45 curved down-turned end flanges adapted to conform to the margins of a can end, said strip being formed with an opening to expose holes punched in the can top, and a spout formed integral with the strip in continuation with one of the flanges and along 50 the margin of the opening in the strip, said strip being recessed on its under side adjacent the end flanges whereby the intermediate portion of the strip will seat on the 55 surface of the can end.

ROBERT M. CLAPP.
